UNITED STATES PATENT OFFICE.

JOHN P. DORAU, OF NORTH FOND DU LAC, WISCONSIN.

HUB-JACK.

1,349,502.

Specification of Letters Patent. Patented Aug. 10, 1920.

Application filed March 11, 1920. Serial No. 364,934.

To all whom it may concern:

Be it known that I, JOHN P. DORAU, a citizen of the United States, residing at North Fond du Lac, in the county of Fond du Lac and State of Wisconsin, have invented certain new and useful Improvements in Hub-Jacks; and I do declare the following to be a full, clear, and exact description of the invention, such as will enable others skilled in the art to which it appertains to make and use the same.

My invention relates to jacks and more particularly to those intended primarily for engagement with hubs of automobiles for relieving the tires of the weight of the machine.

One object of the invention is to provide a simple and inexpensive device embodying a lever, a lifting arm, and novel means for hinging the two together in a manner to permit adjustment for cars having wheels of different diameters.

Another object is to provide an effective cushion for the lifting arm to prevent mar-ring of the wheels thereby.

With the foregoing in view, the invention resides in the novel construction of parts hereinafter fully described and claimed.

30 Figure 1 of the accompanying drawings is a side elevation of a jack applied to the hub of an automobile wheel, before lifting the machine.

Fig. 2 is a view similar to Fig. 1 but showing the wheel elevated by the jack.

Fig. 3 is a horizontal section on the plane of line 3—3 of Fig. 1.

Fig. 4 is a vertical section as indicated by line 4—4 of Fig. 1.

40 Fig. 5 is a perspective view of the reversible plate carried by the lever and in turn carrying the pivot of the lifting arm.

Figs. 6 and 7 are respectively a side elevation and a vertical section of the cushion 45 of the lifting arm, the later view being cut on the line 7—7 of Fig. 6.

Fig. 8 is a detail perspective showing a different form of cushion which may be used if desired.

50 In the drawings above briefly described, the numeral 1 designates a hand lever having its fulcrum 2 located at one end, while a short distance in rear of said fulcrum, the lever is provided with a transverse groove 55 3 whose opposite sides form thrust shoul-

ders co-acting with a rib 4 or other suitable thrust means carried by a reversible plate 5 which is secured by screws or the like 6 to the lever. Plate 5, as shown, is provided with spaced flanges 7 carrying a 60 pivot pin or the like 8 by means of which the load-lifting arm 9 is pivotally connected with the lever 1. By reference more particularly to Figs. 1 and 2, it will be seen that the rib 4 is laterally offset from the 65 axis of the pivot 8. This is done, in order that by reversing the plate 5 upon the lever 1, the distance of the pivot from the fulcrum 2, may be varied, for adapting the jack for use in connection with wheels of 70 relatively small and large diameters. When the plate 5 is positioned as shown in Figs. 1 and 2, the jack is adjusted for use in connection with comparatively large wheels, since the pivot 8 is then located a considerable distance from the fulcrum 2, but when the screws 6 are removed, the plate 5 reversed, and the rib 4 again positioned in the groove 3, the aforesaid pivot is located much closer to the fulcrum 2 and thus the 75 80 lifting-arm 9 may be placed under the hubs of smaller wheels.

Secured to the free end of the arm 9, is the shank 10 of a substantially T-shaped plate whose head 11 is bent laterally around the end of said arm as shown clearly in Figs. 6 and 7. The ends of the head 11 are bent laterally into parallel relation to form a pair of ears 12 between which a suitable cushion 13 is mounted, said cushion 90 being preferably in the form of a roller having a bushing 14 through which a rivet or the like 15 passes, the latter having its ends upset in openings in the ears 12. It is to be observed that the buffer or cushion 95 13 is of greater diameter than the thickness of the lifting-arm 9. It is thus impossible for any parts of this arm to strike the vehicle wheel and possibly mar the same.

In Fig. 8, I have shown another form of 100 buffer or cushion which may be used if desired. In this figure the free end of the arm 9 is rounded as indicated at 16 and the opposite sides of said arm are provided with shallow grooves 17 adjacent said rounded 105 end. A strip of leather or rubber 18 is passed around the rounded end 16 and has its ends secured in the shallow grooves 17 by tacks or other appropriate fasteners 19. Here again, the proportion of parts is such 110

as to prevent either the arm 9 or the fasteners 19 from coming in contact with the wheel.

In use, with the lever 1 horizontal or substantially so, as indicated in Fig. 1, the lifting-arm 9 is placed under the hub of the vehicle wheel or under any other part to be lifted. When the lever 1 is now swung upwardly, for instance as shown in Fig. 2, the lifting-arm 9 and consequently the load is raised. Whenever desirable, the plate 5 may be reversed, for adapting the jack to wheels and the like of different sizes and for lifting the load a greater or lesser distance. Furthermore, by varying the position of the plate 5, the leverage may be varied for lifting cars of different weight.

All features of construction employed are simple and inexpensive and hence the jack may be advantageously manufactured and marketed. Regardless of these characteristics however the device is efficient and reliable and in every way desirable. Since probably the best results may be obtained by the several features described and shown, these details are preferably followed, but within the scope of the invention as claimed, considerable latitude is allowed for making such minor changes as occasion may dictate.

30 I claim:

1. A jack comprising a lever having its fulcrum at one end, said lever having thrust means, a plate carrying a pivot and having

thrust means offset laterally from the pivotal axis and engageable with the thrust means of said lever, said plate being reversible to locate said pivot at either of two distances from the fulcrum when the aforesaid thrust means are engaged, means for securing said plate to said lever in either of its positions, and a lifting-arm mounted on said pivot.

2. A jack comprising a lever having its fulcrum at one end and provided with a transverse groove at a point spaced from said end, a plate having at spaced points a rib and a pivot, said plate being reversible to locate said pivot at either of two distances from the fulcrum when said rib is received in said groove, means for securing the plate to said lever in either of its two positions, and a lifting-arm mounted on the aforesaid pivot.

3. A jack including a lifting-arm, a T-shaped metal plate having its shank secured to one side of said arm near the end thereof, the head of said plate being bent laterally onto the end of said arm, the ends of said head being bent into parallel relation to form ears, and a buffering device mounted between said ears to engage the object to be lifted.

In testimony whereof I have hereunto set my hand.

JOHN P. DORAU.
